WILLIAM G. WILL, OF FAIRVIEW, ILLINOIS.

SYSTEM OF CONTROL FOR THE CARBURETING AND IGNITING DEVICES OF INTERNAL-COMBUSTION ENGINES.

Application filed July 19, 1918. Serial No. 245,788.

To all whom it may concern:

Be it known that I, WILLIAM G. WILL, a citizen of the United States, residing at Fairview, in the county of Fulton and State of Illinois, have invented certain new and useful Improvements in a System of Control for the Carbureting and Igniting Devices of Internal-Combustion Engines, of which the following is a specification.

This invention is a system of control for the carbureting and igniting devices of internal combustion engines, and is more particularly adapted for use upon self propelled vehicles wherein mixture adjustments and ignition changes are made automatically with the movement of the clutch as during the shifting of the gears in the transmission, or when the movable member of the clutch is operating at speeds differing from that of its housing and of the fly wheel.

One object of the invention is to provide a fly wheel with a rotatably mounted element that is adapted to cooperate with the fly wheel and the movable member of the clutch so that speed variations between said member and fly wheel will cause the element to rotate clock-wise, and counter clock-wise, or remaining stationary if the speeds be alike in number.

Another object of the invention is to provide a plurality of spaced and insulated electrically conducting rings carried by the fly wheel and concentric to the shaft and the periphery of the fly wheel, one of said rings being constantly in engagement with a contact carried by the rotatable member, and the other rings being adapted for engagement with a contact switch arm carried by the fly wheel element for controlling electric circuits by speed variations.

A further object of the invention is to provide electric circuits connected with the rings, the switch arm and a source of electric energy, and having therein suitable electro-magnetic devices serving to control subsidiary or auxiliary circuits including switching and operating means.

A still further object of this invention is to provide an electromagnetic control for the valve of the carburetor for automatically varying the mixture passing to an internal combustion engine to make the same richer or thinner and to also vary the

volume of the mixture, depending upon the 55 throttle opening.

One purpose of the invention is to provide electromagnetic switching devices for controlling the primary circuit of an ignition system in accordance with the clutch 60 speed variations relative to crank shaft speeds.

Broadly stated, the system of control comprises a plurality of spaced and insulated rings concentrically arranged, a rotatable 65 element provided with a contact and a contact switch arm adapted to move over and selectively contact with each of said rings, said contact being constantly in contact engagement with one of the rings, electric circuits including a source of energy connected with said rings, an electro-magnetic switching device controlled by the movement of the arm, said devices in turn controlling the primary circuit of the ignition system, and 70 the valve controlling the flow of the gas mixture, said latter valve being operated by electro-magnetic means, the rotatable element being composed of a cylindrical member having a shaft secured therein, one 80 end of said shaft carrying a disk at its outer end and its inner end flexibly connected with the member through a spring or clutch device, said switch arm and contact being mounted on and insulated from 85 the cylindrical member, and when the disk is moved outward by the movable member of the clutch, the shaft spring causes the clutch to engage and thus rotate the cylindrical member and its arm. 90

One practical form of construction with a fly wheel and clutch assembly and one circuiting arrangement for control will be described and illustrated in the accompanying drawings, in which:—

Figure 1 is a vertical sectional view through a conventional fly wheel and disk clutch showing the rotatable member and the rings operatively assembled.

Figure 2 is an enlarged longitudinal sectional view of the rotatable member carried by the fly wheel, 100

Figure 3 is a sectional view on the line 3—3 of Figure 2, and

Figure 4 is a diagrammatic view illustrating one circuit arrangement. 105

In the preferred embodiment of elements about to be described there is illustrated

in Figure 1 a sectional view of a flywheel 5. This flywheel may be of any conventional form and provided with the web 6. As shown in this figure there is mounted 5 a dry plate disk clutch having its stationary housing 7 connected with the flywheel and having its movable member 8 adapted to be moved upon the shaft 9 which carries the flywheel 5 as shown. The movable member 8 of the clutch may be operated in any usual way and the spring 10 serves to press the driving and driven disks together as is usual. The description of the flywheel and clutch is given for illustrative purposes so that the following specification will indicate how the system and the elements thereof are applied and operated.

The web 6 is provided with a hole that passes transversely therethrough in a plane 20 parallel to the longitudinal axis of the shaft 9. As shown this hole is adapted to receive a cylindrical casing 11. The outer end of this casing may be provided with a reduced portion 12 and between this reduced portion 12 and in the body portion 11 there is formed a shoulder 13. The reduced end 12 is adapted to have secured thereon a ring like member 14. The outside diameter of this ring is slightly greater 25 than that of the cylindrical casing 11. The ring 14 is preferably so secured on the reduced end 12 that it may have a slight rotary motion relative to the reduced end. Extending from this ring 14 there is provided 30 a resilient member 15 that has its other end secured to the flywheel in any suitable manner.

This member 15 serves to secure the casing and its other parts in alignment. The 40 function will be more clearly seen hereafter. The reduced end 12 of the cylindrical casing 11 is provided centrally with a hole that is adapted to receive a shaft 16. This shaft is adapted to slide in this hole which serves 45 as a bearing for the shaft for both its rotary and sliding motions. The shaft 16 is provided with a reduced section 17 that lies within the casing 11. The shaft is further provided with a reduced section 18 that 50 is of less diameter than the section 17. The section 18 rotates and slides in a hole formed in the rear wall 19. This wall or partition may be secured in the end of the cylindrical casing in any suitable manner.

55 Surrounding the section 17 of the shaft is a helical spring 20 that has one of its ends connected with the spring retainer 21 which retainer is secured to the shaft section 17. As shown in Figure 2 this spring 60 is provided at its other end with a clutch member 22, which clutch member may be provided with suitable teeth to engage with complementary recesses formed in the end of the cylindrical casing 11. The teeth for 65 the clutch member 22 being indicated at

23 and the recesses therefor being indicated at 24. This clutching arrangement is purely conventional and any other type may be employed.

The outer end of the shaft 16 is provided with a disk 25. As shown in Figure 2 this disk 25 is provided with the beveled edges 26 and 27 so that it is substantially V-shaped in cross section through the periphery. The cylindrical casing 11 70 has provided at its extreme rear end a flange 28 which flange is spaced from the back wall or partition 19. The end of the reduced shaft section 18 normally lies spaced a slight distance away from this flange 28. The casing may be provided 75 with openings between the wall 19 and the flange 28, one side of each of the openings being indicated at 29 and 30.

Secured upon the flange 28, which is preferably circular, is a disk 31 formed of insulating material. Secured to the insulating disk 31 there is another disk 32 that may be formed of metal. Any usual means 80 may be employed for securing the disks together one of which is indicated by the pins 33. Extending from the disk 33 there is a sleeve 34 having thereon a collar 35. In the sleeve 34 there is mounted a shaft 36 that may be formed integrally with the disk 90 32. Mounted on the shaft 36 is a switch arm 37 having a contact point 38 at its outer end. As shown in Figure 2 the inner end of the arm 37 preferably lies in contact with the collar 35.

Extending outwardly from the arm 37 there is provided a cup-like member 39 that encloses the outer end of the shaft 36. As the cylindrical casing 11 is adapted to be mounted in the flywheel 5 it is also adapted to have a rotary motion in this hole. In order to restrict excessive rotation the casing 11 is provided with a lug 41 that projects radially between the two ends of the springs 42 and 43. These springs are 100 helically formed and are preferably arranged circumferentially as shown in Figure 3. Between the other ends of the springs there is provided a curved brace 44 having the flanges 45 and 46 at its end. These 115 flanges 45 and 46 serve as abutments for the ends of the springs 42 and 43.

The movable member 8 of the clutch is provided interiorly with a V-shaped groove 47. As shown in Figure 1 this groove is formed adjacent the inner open end of the member. The beveled edge disk 25 is adapted to ride and roll in this groove. When the clutch member 8 is moved to the right the disk 25 is moved with it and the shaft 16 120 with the reduced sections 17 and 18 slide in their respective bearings formed in the cylindrical casing 11. The general assembly of this casing may be designated A in order to avoid confusion. The resilient mem- 130

ber 15 serves to maintain the element A in its proper position relative to the longitudinal movement and the springs 42 and 43 cooperating with the abutment 41 serving 5 to limit the rotative movement.

Upon the side of the flywheel 5 opposite to that upon which is mounted the clutch there is provided a plurality of spaced insulated conducting rings 48, 49, 50, and 51, 10 the insulation for the rings being indicated at 52. These conducting rings and their insulating rings may be mounted and secured in the flywheel in any approved manner. As shown in Figure 1 these rings are 15 arranged concentrically to the shaft 9 as well as to the periphery of the flywheel 5. The contact member 39 has a substantially constant engagement with the conducting ring 50 as indicated at 40 in Figure 2. 20 This is shown more particularly in Figure 1 and in the diagrammatic view Figure 4.

At a suitable point the ring 50 may be connected with a source of electric energy such as is indicated by the battery 53 by 25 means of the conductor 54. The other terminal of the battery 53 has connected to it a conductor 55 that is provided with the branches 56 and 57. At a suitable point the conductor 55 is provided with a switch 58. 30 The branch conductor 56 connects with one terminal of the electro-magnet B and the conductor 59 connects with the other terminal and with the ring 49. The branch conductor 57 connects with one terminal of the 35 electro-magnet C and the conductor 60 connects with the other terminal with this electro-magnet and with the ring 51.

The point of connection for the conductors 40 54, 59 and 60 with the rings 49, 50, and 51 may be brushes 61, 62, and 63 if desired. Any usual means may be employed. The conductor 55 has connected to it at 64 a jumper 65 that connects with the conductors 66 and 67. The conductor 66 leads to the 45 terminal 68 for the primary side of the induction coil or other transforming device D. The terminal 69 of this coil has connected to it the conductor 70 that has its other end connected with a contact point 50 71. A jumper 73' connects at 73 with the conductor 70 and with the contact 74 that engages the ring 48. The contact 71 is spaced from the contact 72 and these contacts are bridged by a switch arm 75. The 55 switch arm 75 is mounted upon a cruciform assembly that is pivotally mounted at 76. This assembly is provided with the arms 77, 78, 79, and 80 radiating from the pivot point 76. The arm 78 carries at its outer end an armature 81 that is adapted to operate with the core of the accelerating electro-magnet B.

The arm 80 is also provided with an armature 82 that is adapted to cooperate with 60 the core of the de-accelerating electro-mag-

net C. The arm 79 is so arranged that its end is interposed between the springs 83 and 84 that have their other ends secured in the abutments 85 and 86. These springs 83 and 84 are preferably of the same resiliency 70 so that the several arms of the assembly are maintained normally in position shown in the diagrammatic Figure 4. The outer end of the arm 82 is provided with a bridging contact 87. This contact is preferably 75 insulated from the arm 80 and as shown is approximately U-shaped to engage with the contact points 88 and 89. The contact 88 has connected to it one end of the conductor 67. The point 89 has connected to it the conductor 90 that connects with one terminal of the electro-magnet E. The other terminal of this magnet has connected to it a conductor 91 that connects with the conductor 54 at the point indicated at 92. 80

The conductor 91 has connected to it at 93 a conductor 94 that connects with the contact point 72. The electro-magnet E may be mounted in any suitable manner so that it will cooperate with the armature 95. One 90 method of mounting the electro-magnet E so that it may be operatively connected with the carbureter F is shown by the arm 96 secured to the carbureter. The armature 95 is carried at the end of an arm 97 that projects from a pivotally mounted sector gear 98, the pivotal mounting being indicated at 99. This gear 98 is adapted to operate with a pinion 100 mounted upon the 95 throttle valve shaft 101.

A clutch engaging mechanism which holds the clutch out until the right instant and then allows it to engage, as shown diagrammatically in Figure 4. The shaft 76 upon which the cruciform assembly is rigidly 105 mounted has also a cam 102 so shaped that it raises pivoted lever 103 when arm 81 is attracted by accelerating magnet B; the cam, however, being of such a character as not to lift the lever when the opposite arm 80 is 110 attracted by de-accelerating magnet C. Lever 103 has a raised portion 103' which hooks over a sector element 104. This sector depends from the clutch yoke 105 to which the usual clutch pedal is attached: 115 the sector being rigid with the yoke and movable therewith when the pedal is operated to engage or disengage the clutch when shifting gears. When disengaging the clutch, the sector moves to the right, in Figure 4, and this movement is necessary to permit the end of lever 103 to hook over the sector for the purpose of holding the clutch disengaged as long as magnet B is energized. The clutch engaging mechanism is 120 operable, therefore, only when, or after the clutch has first been disengaged. When magnet B is de-energized lever 103 drops by spring pressure and releases sector 104, permitting the engagement of the clutch. 125

Assuming the pedal of clutch yoke 105 to have been shifted to move clutch member 8 outwardly for disengaging the clutch, it will be seen that, as the clutch is disengaged, 5 wheel 25 is pulled to the right in Figure 2, engaging positive jaw clutch 22 with casing 11, causing the latter to rotate with shaft 16 and either to the right or left through an arc sufficient to engage contact 10 38 with one of the conducting rings of the fly-wheel; after which wheel 25 slides in groove 47 of the clutch member. When clutch is engaged, that is, when member 8 moves inwardly, wheel 25 is shifted to the 15 left which releases jaw-clutch 22; casing 11, turning back by pressure of circular springs 42 or 43 so that switch-arm 37 is at "off" position. This jaw-clutch is necessary to prevent opposite solenoid from acting after 20 clutch is engaged. It also prevents automatic device from affecting engine speed, if a faulty clutch slips, et cetera. When the clutch is fully engaged and fly-wheel 5 and member 8 rotate at the same speed, wheel 25 is acted upon equally by both, and, consequently, is not rotated. At this time the 25 switch is open; switch arm 37 remains, therefore, at its normal position in engagement with ring 50 and none of the several 30 circuits are closed. But when shifting gears the clutch changes its rate of speed and, in order to provide for a smooth engagement of the clutch and engine, the engine must be accelerated or de-accelerated to correspond 35 with the change. In this connection, it is to be noted that by reason of the manner in which wheel 25 is supported between clutch member 8 and fly-wheel 5 the position of switch arm 37 with respect to the conducting 40 rings will change whenever the respective speeds of the fly-wheel and the clutch member differ the fractional part of a revolution. Consequently, when the lever is moved from first to second speed position, 45 the clutch is disengaged by the side-thrust of the lever and its rate of speed changed to that of corresponding gear. Movable member 8 is then rotating at a slower speed than fly-wheel 5 and, hence disc 25 is caused to turn slightly in an opposite direction 50 from the way fly-wheel is turning. Also it will be noted that at this time the switch 58 is closed. This turning movement shifts the switch-arm 37 until contact 38 engages ring 55 51 which closes the circuit to the de-accelerating magnet C; the current being traced from one pole of battery 53 through conductor 54 and brush 61 to ring 50 from whence it passes into the switch arm 37 60 through contact 58, passing from the contact 38 of the arm to ring 51 and thence through brush 63 and conductor 60 to magnet C, from which it returns to the other pole of the battery through conductors 57 65 and 55, thereby completing the circuit and

energizing the magnet. Armature 82 is attracted by the energized magnet, causing the cruciform member to pivot against tension of spring 83 so that arm 80 moves downwardly, bringing the U-shaped contact member 87 into engagement with contacts 88 and 89. This closes the electro-magnet circuit which includes contact 89, conductor 90, electro-magnet E, conductors 91 and 54, battery 53, conductors 55, 65 and 67, and 75 contact 88; thus operating the sector gear 98 and pinion 100 thereby shutting off the explosive mixture. Moreover, arm 77 of the cruciform member also moves to the right when armature 82 is attracted and thus 80 shifts 75 so as to break electrical connection between contacts 71 and 72 of the primary circuit. This circuit includes contact 71, conductor 70, terminals 69 and 68 of the coil, conductor 66, jumper 65, conductor 55, battery 53, conductors 54, 91, 94 and contact 72, and switch arm 75. It is thus seen that the breaking of the primary circuit and the closing of the throttle or magnet circuit E is instantly effected 90 upon the energizing of the de-accelerating magnet C. On the other hand, when the clutch in shifting gears is caused to rotate faster than the fly-wheel, the speed of the engine is accordingly accelerated to correspond therewith by the energizing of the accelerating magnet B, effected in the following manner: switch arm 37 is moved outward toward rings 48 and 49 by reason of the faster speed of the clutch member as 95 compared with fly-wheel 5. It will first contact with ring 49, closing the circuit through brush 62, conductor 59, magnet B, conductors 56 and 55, battery 53, conductor 64, brush 61, ring 50 and switch arm 37; thus 100 energizing magnet B, and attracting armature 81. This causes arm 78 to move downward and arm 80 to move upward, disengaging contacts 88 and 89 and de-energizing magnet E, permitting the parts controlled thereby to return to normal position. At the same time, switch 75 is moved to the 105 left in Figure 4 temporarily forming an electrical connection between contacts 71 and 72 and closing the primary circuit for an instant only, thereby producing a spark. However, since switch arm 37 engages contact D of ring 48 shortly after it engages ring 49, it may be seen that the primary circuit of the coil is thereby changed and 110 may be traced from terminal 69 through jumper 72 and brush 74 to the contact C of ring 48, then through switch arm 37, ring 50, brush 61, conductor 54, battery 53, and conductor 55 to jumper 65, and thence back to terminal 68 of the coil, by way of conductor 66. The primary circuit is thus maintained even though contacts 71 and 72 are electrically disconnected. This circuit is practically a shunt from B-magnet circuit and the 115 120 125 130

current will therefore be divided in proportion to their respective resistances. The contact maker or breaker of the coil allows the current to pass through shunt only during short intervals. The speed of the engine is thus accelerated to correspond with the speed of the clutch member 8 and it is obvious that it may, at times, exceed that of the clutch member, but in such an event, 10 the variation in speed above that of the clutch member causes switch arm 37 to be moved out of engagement with contact Z and ring 49; thereby breaking, in the first instance, the primary circuit of the coil, 15 since switch 75 is likewise off contact at such time, and, in the second instance, breaking the circuit of magnet B and releasing arm 78. If the variation in the speed is great enough and, it will be practically, arm 37 20 is immediately moved in contact with ring 51, energizing magnet C so that arm 78 when released by magnet B will not drop in normal position but will continue upward as arm 80 is pulled down by magnet B. At 25 the instant it passes beyond normal, a spark will occur in the primary circuit caused by switch arm 75 momentarily completing the circuit at contacts 71 and 72. In this connection it may be pointed out that the primary reason for the employment of ring 48 30 is because of the counter electromotive force of the primary coil and magnet B; the idea being that the spark above referred to will not be as destructive if connection between contact Z and contact 38 is broken instant before the connection is broken between ring 49 and switch arm 37. Otherwise three rings are all that are necessary and brush 74 would, then, be on ring 49. 35 At the same time that the released arm 78 is moving upward and attracted arm 80 is moving downward, lever 103 drops from engagement with yoke-sector 104, allowing the latter to be moved forwardly and consequently permitting the clutch to be engaged through the rotation of yoke 105 in the usual manner. As the clutch is engaged, shaft 16, it is to be recalled, moves inwardly of the casing 11 thereby disengaging jaw 40 clutch 22 and releasing the casing which is turned by either spring 42 or 43, as the case may be, to replace the switch arm 37 in its normal position that is, in alignment with ring 50 and out of contact with ring 51. 45 This breaks the circuit of magnet C permitting the throttle valve of shaft 101 to be again opened and the arm 77 of the cruciform to be normally located, by action of springs 83 and 84, with the switch arm 75 50 bridging contacts 71 and 72, and thereby re-closing the primary circuit at such points. These movements will take place in a very short interval of time but each movement has exact precedence over the other: the object 55 being to allow the disengaged clutch member to engage the face of the fly-wheel at an instant when no power is applied from within the engine cylinders, thus eliminating jar to car mechanism if speed differed to an extent that would cause jar otherwise. In order to understand this, it is necessary to consider the time during which the various units act, since gear changing must be as rapid as conventional practice has determined and must be without jar. In shifting from a 60 low to a higher gear, assuming the engine to be running at a given rate of speed, for example 600 R. P. M., it is obvious that when the master clutch is disengaged therefrom the speed of the clutch becomes less than that of the engine. The instant the clutch starts to turn slower than the fly-wheel however, the de-accelerating magnet C is energized and the engine speed thereby de-accelerated at a constant rate between any 65 given number of R. P. M. When the engine speed has dropped to a point corresponding to the clutch speed the circuit through the magnet will be broken and it is to be noted that the clutch is held out for a short time 70 by the foot whenever shifting from a low to a higher gear. If the foot is kept on the clutch too long and the engine runs slower than the clutch the switch arm moves to close the circuit through the magnet B. If now the foot be raised from the clutch pedal the clutch will not go in being held out by the lug 103 until the engine has speeded up to its proper speed. Also, the engine "lags" a 75 certain time before gas is vaporized and drawn into the cylinders. 80 As previously mentioned, the operation of de-accelerating magnet C does not affect sector 104 and consequently the clutch is not held out at such time but may be engaged by side thrust of the clutch lever in the usual way; the circuit of the magnet being broken by the disengagement of jaw clutch 22 and the consequent release of casing 3 which carries switch arm 37. If the power 85 is shut off when the clutch is engaged the only factor causing jar is energy stored in the flywheel which is, however, being braked by compression. This does not jar the car if lever is not moved rapidly. In shifting 90 from a high to a lower gear, the clutch turns at a greater speed and the switch arm 37 is shifted to actuate the accelerating magnet B for increasing the speed of the engine a 95 corresponding extent and likewise lifting lever 103 into engagement with sector 104 whereby the clutch is held out. The greater speed of the clutch member 8, has, at such time, so rotated wheel 25 that the arm 27 has been moved through an arc sufficiently great 100 to bring it in contact with contact Z, thereby abridging the primary circuit through jumper 73', as previously described. The arm remains in this position until the speed 105 of the engine or fly-wheel has been accelerated. 110

- ated to exceed the speed of the clutch, in which instance, the variation immediately moves the arm in contact with ring 51, energizing de-accelerating magnet C but 5 breaking the primary circuit and de-energizing magnet B. The de-energizing of magnet B releases the clutch-engaging mechanism and permits the clutch to be engaged; the primary circuit being also re-established 10 at contacts 71 and 72. In the interval of time during which magnet B de-magnetizes and the clutch engages, no spark is produced in the engine cylinders and consequently there is no acceleration. The curve of engine acceleration will possibly cease at the 15 instant the clutch changes and while fly-wheel will be rotated slightly faster than the clutch member, as it should be, to prevent a too rapid de-acceleration of engine. As soon as the clutch is engaged, the magnet-circuit is then broken by actuation of jaw clutch 22 as before pointed out.

The foregoing description and the drawings have reference to what may be considered the preferred, or approved, form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent is:

35. 1. A system for automatically controlling the ignition and fuel of an internal combustion engine, which comprises a fly wheel having a rotatable element mounted transversely thereof, a contact and a switch arm carried by said member, a plurality of spaced and insulated rings on said fly wheel and engageable by the switch arm, said contact engaging constantly with one of the rings, electric circuits including a source of electric energy connected with the rings, means for operating said member and therefrom the switch, and electro-magnetic devices for automatically controlling the ignition circuit and the valve of the carbureter.
40. 2. A system for automatically controlling the ignition and fuel of an internal combustion engine, which comprises a rotatable element mounted in a fly wheel and having rotatable and slideable shaft therein, a plurality of spaced and insulating rings arranged concentrically to each other, said element being provided with a contact for constantly engaging with a ring and a switch arm adapted to selectively engage with the rings, electric circuits including a source of energy connected to said rings, an electro-magnetic switching means controlled by the movement of the switch arm with the rings, said switching means controlling an electro-magnetic adapted to actuate a carbureter valve.

3. A system for automatically controlling the ignition and fuel of an internal combustion engine, which comprises a rotatable element mounted transversely of a fly wheel, and a rotatable and slideable shaft therein, one end of the shaft projecting from the element and provided with a disk adapted to cooperate with the movable member of a clutch, said shaft being flexibly connected with the element, means for clutching the shaft to the element upon slidably moving the shaft, one of the elements being provided with a contact and switch arm both of which are insulated from the element, a plurality of spaced and insulated rings carried by the fly wheel of an engine and concentrically arranged thereon, electric circuits including a source of electric energy connected to said rings, said contact being in constant engagement with one of the rings, and the switch arm being adapted to selectively engage with the rings upon rotation of the fly wheel carried element, electric circuits including a source of energy connected to said rings, electro-magnetic switching devices controlled by the switch arm and rings, said devices serving to control a carbureter valve and the primary circuit of an ignition system.

4. A system for automatically controlling the ignition and fuel of an internal combustion engine, which comprises a plurality of electric circuits including a source of electric energy, means carried by the fly wheel and controlled by the movement of the movable member of a clutch by the variations in speed between said flywheel and clutch member, and electromagnetic means in the circuits and controlling the primary of the ignition circuit and the actuation of the throttle valve of the carbureter.

5. A system for automatically controlling the ignition and fuel of an internal combustion engine, which comprises a plurality of spaced and insulated electric conducting rings mounted in one lateral face of a fly wheel, a rotatable element having a cylindrical body and a longitudinally extending rotatable and slideable shaft, said shaft being surrounded by a helical spring, one end of which is connected with the shaft and the other end to a clutch member, the other clutch member being carried in and by the body, a bevelled edge disk carried on the end of the shaft and adapted to roll in a V-shaped groove formed in the inner periphery of the movable member of a clutch, means for retaining the element in position, electric circuits connected with said rings, and means carried by the element for controlling the circuits.

6. A system for automatically controlling the ignition and fuel of an internal combustion engine, which comprises a selection switching device operable by the movable

member of a clutch, electric circuits including a source of energy connected with the switching device, a plurality of electro-magnets each having their windings separately and independently connected with the device and circuits, a rotatable member having armatures thereon to cooperate with the electro-magnets and separately circuit closing means for controlling the circuit leading 10 to the primary side of the ignition circuit, a carburetor including a rotatable valve shaft having at one end a pinion, a pivotally mounted sector gear to cooperate with the

pinion, and having a projecting arm including an armature, and an electro-magnet in 15 another circuit adapted to act on the armature for rotating the valve shaft, said electro-magnet being controlled by the switching device and circuit closing means.

In testimony whereof I affix my signature 20 in presence of two witnesses.
